UNITED STATES PATENT OFFICE.

BENJAMIN BRODIO, OF NEW YORK, N. Y., ASSIGNOR TO THE SUPERHEATER COMPANY, OF NEW YORK, N. Y.

FURNACE-WALL CONSTRUCTION.

Application filed June 30, 1925. Serial No. 40,605.

My invention relates to furnaces and has particular reference to the type of furnace adapted to be used under steam boilers, and in which one or more of the combustion chamber walls are lined either with water screens, or radiant heat superheaters, or both.

In modern installations of this character very large combustion chambers are provided, necessitating the placing of the boiler at a considerable height above the grate level or the bottom of the furnace, and this latter consideration necessitates the use of high furnace walls which are expensive to construct. In structures of this type where the combustion rate is usually very high, the walls of the combustion chamber or furnace are frequently lined with screens formed of heat absorbing tubes and my invention contemplates the arrangement of such tubes so that they will form a lateral support for the furnace walls and thereby permit the use of a wall construction which is not only much lighter and more inexpensive to construct than the usual form, but which may also be made in a readily removable form, so that easy access may be had to the tube structures for the purpose of repairs or replacement.

The tubes forming the screen lining the furnace walls are subjected to the intense direct radiant heat of the combustion chamber and as a consequence, the heat transfer rate through these tubes is relatively high as compared with the rest of the boiler. They are also subjected, in many cases, to accumulations of slag, particularly in installations where the combustion rate is high and a considerable quantity of slag is carried up with the combustion gases. This condition is more particularly pronounced in cases where pulverized fuel is employed, as in such cases the slag particles, because of their minute character, are carried by the combustion gases in larger quantities than is the case with hand or stoker fired coal burning installations. My invention contemplates a structure which will tend to eliminate or minimize the trouble due to slag accumulation, which will in the case of water screens improve the generating performance thereof, and which will also provide other and further advantages which

will appear more fully in connection with the following detailed description of my invention. 55

As illustrative of my invention, I have shown in the accompanying drawings, a standard boiler of the cross drum type, to the furnace of which has been applied both 60 water screens and a radiant type superheater constructed in accordance with my invention.

Figure 1 is a diagrammatic elevation of the boiler setting with a portion of the casting broken away to show the position of the tubes. 65

Figure 2 is a diagrammatic vertical section taken along the lines 2—2 of Figure 1.

Figure 3 is a section on an enlarged scale 70 taken on the line 3—3 of Figure 2, and,

Figure 4 is a section on an enlarged scale taken on the line 4—4 of Figure 2, showing a modified form of wall construction. 75

Referring to Figure 2, the numeral 10 indicates the drum of a conventional cross drum water tube boiler, connected in the usual manner by suitable circulators 11, with the bank of generating tubes 12, and as the specific form of boiler to which my invention may be applied is immaterial it is not believed necessary to describe the boiler in any detail. The boiler is shown as mounted above the combustion chamber 13, which is of the type adapted for firing by means of a 80 pulverized fuel burner shown at 14, although it is to be understood that the invention is not limited to use with this method of firing, but may be employed in connection with any of the known forms. In the embodiment 85 shown, chosen for illustrative purposes only, the combustion chamber is rectangular in form and is provided with water screens forming a lining for the two side walls thereof, and with a radiant type superheater 90 lining the rear wall. It will be obvious, however, that the invention is equally applicable to combustion chambers having curvilinear as well as plane walls, and that the disposition of either the water screens or 95 superheaters or both may be varied with reference to the wall surfaces as the requirements of the individual installation dictate. 100

It will be further apparent that the inclusion of both water screens and superheater in the combustion chamber is not essential to the

exercise of the invention, which is concerned only with the specific form and disposition of the tube structure forming the water screen or superheater with reference to that portion of the wall structure which it lines. In the form shown, each of the water screens comprises a bottom or inlet header 15, placed at a slight angle with the horizontal in order to facilitate circulation there-through, and 10 connected at its lower end by means of a suitable down flow pipe 16 to the drum of the boiler below the water level therein. A similar top or outlet header 17, which is also slightly inclined to the horizontal, is 15 connected by means of a suitable up-flow pipe 18 to the boiler drum 10, and the screen itself is formed by a plurality of parallel water tubes 19, suitably connected at their ends into the headers 15 and 17. As hereinbefore pointed out, the invention is concerned entirely with the specific disposition of the screen and as the particular manner in which the screen is connected into the boiler is immaterial, in so far as the invention 25 is concerned, the necessary water circulation through the screen may be provided by connection to some source other than that of the boiler, if desired, without departing from the scope of the invention. Headers 30 15 and 17 are preferably placed outside the boiler wall in order to remove the joints between the screen tubes and headers from exposure to the high temperatures existing within the combustion chamber and to make 35 them readily accessible, but this position of the headers is not essential.

The superheater is constructed in much the same manner as are the water screens, comprising a bottom inlet header 20, and an 40 upper outlet header 21, the two headers being connected by a plurality of parallel tubes 22, forming the superheater. The inlet header 20 is connected with the steam space of the drum 10 by means of the steam pipes 45 23 and 24, and the superheated steam is delivered through the outlet 25 in the header 21. As in the case of the water screen and for the same reasons, the headers 20 and 21 are preferably, but not necessarily, placed outside the boiler casing.

In the exercise of my invention, the tubes forming either a water screen or superheater, instead of being placed vertically, are placed at an angle to the vertical and slope inwardly over the combustion chamber. In the form illustrated the projection of the tubes 19 as viewed in Fig. 1 is vertical, but it will be readily apparent that these tubes might equally well be placed at an inclination to the vertical in this direction in addition to their inclination to the vertical plane of the furnace wall indicated in Fig. 2. Likewise the tubes 22 are shown as lying in the plane of the paper in Fig. 1, but this is also a matter of choice as these tubes may,

if desired, be inclined with respect to this plane.

The desired inclination may be given to the tubes, while retaining the headers outside the furnace walls, in a number of different ways, and I have shown two ways in which this may be accomplished. In Figure 1, I have shown the inclination accomplished by bending the tubes 22 outwardly 75 at each end from an intermediate inclined section, so that the ends of the tubes may be joined to the headers outside the boiler in any desired manner, such for example as that described in my Patent No. 1,363,713, issued December 28, 1920. In Figure 2, 80 the inclination of the tubes of the water screen is accomplished by placing the lower header with its cross section at such an angle that the upper face thereof is at an angle to the horizontal, and the screen tubes which 85 enter this face normal thereto, with respect to the plane of the paper in Figure 2, are consequently positioned at an angle to the vertical. Header 15 is preferably placed outside of the lower section 26 of the furnace wall, and as will be noted from Figure 2, the inward inclination of the tubes will bring the upper ends of the straight portions thereof within the line of the upper boiler wall section 27. As previously 90 noted, it is desirable to have the headers outside the boiler setting and in order to make this disposition of the header 17 possible, the upper ends of the tubes 19, are curved, as at 19', and enter the header 17 outside 95 the furnace wall. It will be readily understood, however, that various other forms of connections may be used to accomplish this 100 result.

The wall construction above and below the screen headers may be of any of the usual forms. The inclined screen tubes 19 or 22, however, make possible the use of a more advantageous form of wall over the area covered by the tubes, as the latter may be employed as a support against which the wall may be placed and held in position by gravity.

As indicated in Figure 1, this portion of the wall may comprise a number of refractory blocks or slabs 28 covered by an outer insulating covering 29 of any suitable material. A suitable supporting member such as the angle 30 serves to support the lowermost series of the sections which form this portion of the wall surface and which are supported laterally by the tubes 19 or 22. The upper sections of this portion of the wall surface also receive lateral support from the tubes and may either rest directly upon the series of sections directly below or may rest upon additional transverse supporting members, similar to the angles 30. While it is not essential that this section of the wall be built up in separate units, such 115 120 125 130 135

construction affords the advantage of ready removability for access to the screen tubes in case repair or replacement of the latter is necessary.

- 5 In Figure 4 I have shown a modified form of wall construction as applied to one of the screens, although it will be obvious that this construction may also be applied to a superheater. In this form the tubes have inter-
 10 posed between them on the side away from the combustion chamber, a series of removable plates 31, of the type which are described in my copending application Serial No. 752,374, filed November 26, 1924.
 15 This form of construction provides a continuous metallic wall against which a suitable refractory wall may be supported in the manner just described in connection with Figure 1.

20 In the forms which I have illustrated the inclination of the tubes is shown as comparatively slight, but the amount of inclination is to be determined in each case by specific boiler conditions where the application is made and it may be at a much greater angle than is indicated in the particular application shown herein. In any case, however, the inclination of the screen offers a support for the outer part of the wall, whereby the latter may be more readily and cheaply installed than is the case where the wall must be self supporting, and this construction furthermore admits more readily of the furnace walls being made in removable units. This feature is of great practical importance as with this construction the side walls may be made at a very considerable reduction in cost and the small and readily removable units of the wall, which are merely laid against the inclined tubes, afford easy access for the purpose of repair or replacement of any of the tubes which may have been burnt or otherwise damaged.

25 The inclination of the side wall tubes, particularly in cases where a substantial inclination is employed, will result, in the cases where grates are used and an incandescent fuel bed is positioned at the bottom of the furnace, in a better rate of heat transfer through the tubes than would be the case if they were vertical, as the radiant heat will strike the tubes in a line more nearly normal to the surface thereof than would be the case with a vertical screen.

30 A substantial inclination of the tubes will also minimize if not entirely eliminate, the usual slag accumulation on the tubes, as slag adhering to the upper portion of the tubes will, instead of tending to flow in a molten condition down the length of the tubes, tend to drop from the lower surface thereof, directly to the fuel bed, or to the floor of the combustion chamber.

35 In addition to the advantages previously mentioned, which apply both to water screens

and superheaters, a further and important advantage is derived from the use of my invention as applied to water screens. The rate at which steam can carry heat away from tube walls is much less than that obtaining where the heated medium is water and the over-heating of the tubes, in the case of the superheater, is prevented by so locating or protecting the superheater that the amount of heat which the tubes can absorb is properly limited. On the other hand, screen tubes, being water filled and capable of absorbing heat at a much higher rate than steam filled tubes, are usually placed where the temperature conditions are extremely severe. As a result, large quantities of steam are produced in these screen tubes and the steam thus formed, displacing a portion of the water, which has a higher capacity for heat absorption and for which capacity the screen is designed, tends to cause the tubes to become overheated and in many instances burned.

40 By inclining the screen tubes, the steam, rising vertically as formed, will break away from the surface on the inner side of the tubes which is exposed directly to the combustion chamber, and travel upward through the outer portion of the tubes into the outlet header. By this action, the insulating bubbles of steam are more rapidly removed from the surface exposed to the fire than is ordinarily the case, and the danger of burning the tubes is minimized. In addition, the evaporating capacity of the tubes is improved because of the fact that the inner surface of the tube is more nearly constantly in direct contact with water, which has, as previously noted, a greater heat absorbing capacity than steam.

45 The action of the steam in leaving the lower face of the screen tubes will also tend to prevent the formation of steam bubbles or pockets which occupy the full cross section of the tubes, and which in moving upward carry large slugs of water into the boiler drum. By minimizing this tendency to form steam pockets in the tubes and instead, to discharge the steam in a more or less continuous column along the outer face of the tube, the discharge of large slugs of water from the screen into the drum is reduced, and the water level in the latter is thereby kept more nearly even than would be the case if a straight vertical screen were used.

50 I claim:

1. In combination a boiler, setting walls enclosing the boiler and extending therebelow to enclose a combustion chamber, there being an aperture in one of said walls, a screen arranged within said aperture, said screen comprising a plurality of heat absorbing tubes rising at an inclination to the vertical toward the combustion chamber, and an

outer wall of refractory material resting upon said tubes, maintaining contact therewith by gravity, and closing said aperture.

2. In a boiler and furnace setting, a wall comprising an upper section, a lower section spaced therefrom, and an intermediate portion closing said space, said intermediate portion comprising a plurality of upwardly inclined heat absorbing tubes, and an outer refractory wall portion resting upon said tubes and deriving its sole lateral support therefrom.

3. A boiler and furnace setting comprising a wall having an upper section, a lower section spaced therefrom, and an intermediate portion closing said space, said intermediate portion comprising a plurality of upwardly inclined heat absorbing tubes, top and bottom headers to which said tubes are connected, said headers being located outside the boiler setting, the exterior of said intermediate portion being formed of refractory material resting upon and laterally supported by said inclined tubes.

4. In a boiler and furnace setting a lower wall section, a header lying adjacent to and outside said lower section, a plurality of heat absorbing tubes connected to said header and rising therefrom at an inward inclination from the vertical, an upper wall section, a second header outside said upper section, said tubes being curved outwardly at their upper ends to connect to said second header, and a refractory wall resting upon and laterally supported by said tubes intermediate said headers.

5. In a boiler and furnace setting a lower wall section, a header lying adjacent to and outside said lower section, a plurality of heat

absorbing tubes connected into the top of 40 said header and rising therefrom at an inward inclination from the vertical, an upper wall section, a second header outside said upper section, said tubes being curved outwardly at their upper ends to connect into 45 the side of said second header, and a refractory wall resting upon and laterally supported by said tubes intermediate said headers.

6. In a boiler and furnace setting, a wall 50 having spaced upper and lower sections, a pair of inclined headers outside said wall and adjacent said space, a plurality of heat absorbing tubes connecting said headers and bridging said space, said tubes being inwardly inclined throughout the major portion of their length, and a refractory wall closing said space and resting upon and laterally supported by said inclined tubes.

7. In a boiler and furnace setting, a wall 60 having spaced upper and lower sections, a water screen comprising a plurality of upwardly and inwardly inclined water tubes bridging said space, and a refractory wall resting upon and laterally supported by said 65 inclined tubes, the portion of the wall supported by said tubes comprising a plurality of removable sections.

8. In a boiler and furnace setting, a wall having an aperture therein located opposite 70 the combustion chamber below the boiler, headers located adjacent the upper and lower boundaries of said aperture, a plurality of water tubes upwardly and inwardly inclined connecting said headers, and a refractory wall closing said aperture and resting upon and laterally supported on said tubes.

BENJAMIN BROIDO.
